Primary Examiner — Susan Bennett Hattan*Assistant Examiner* — Jennifer Wright(74) *Attorney, Agent, or Firm* — Samuel M. Korte; Max M. Ali**CLAIM**

The ornamental design for a watch device, as shown and described.

DESCRIPTION

FIG. 1 is a front perspective view of a watch device according to the present invention;

FIG. 2 is a rear perspective view of the watch device;

FIG. 4 is a front view of the watch device;

FIG. 5 is a bottom view of the watch device;

FIG. 6 is a rear view of the watch device;

FIG. 7 is a left side view of the watch device; and,

FIG. 8 is a right side view of the watch device.

The broken lines shown in FIGS. 1 through 8 represent portions of the electronic device that form no part of the claimed design.

1 Claim, 4 Drawing Sheets(56)
